Term of patent 14 years

Int. Cl. D20—01

U.S. Cl. D51—3

FIGURE 1 is a left front perspective view of a first embodiment of a cigarette vending machine cabinet showing my new design;

FIGURE 2 is a front elevational view of both the first embodiment and a second embodiment of a cigarette vending machine cabinet showing my new design;

FIGURE 3 is a left side elevational view of the first embodiment thereof, the right side elevational view being substantially a mirror image thereof;

FIGURE 4 is a top plan view of both the first and second embodiments thereof;

FIGURE 5 is a left side elevational view of the second embodiment thereof, the right side elevational view being substantially a mirror image thereof; and

FIGURE 6 is a left front perspective view of the second embodiment thereof.

The rear and bottom of both the first and second embodiments of the cigarette vending machine cabinet are plain and unornamented.

I claim:

The ornamental design for a cigarette vending machine cabinet, substantially as shown and described.
